UNITED STATES PATENT OFFICE.

ALOIS HELFENSTEIN, OF VIENNA, AUSTRIA-HUNGARY.

ELECTRIC INDUCTION HEATER OR FURNACE.

1,093,328.

Specification of Letters Patent. Patented Apr. 14, 1914.

Application filed June 5, 1912. Serial No. 701,893.

To all whom it may concern:

Be it known that I, ALOIS HELFENSTEIN, a citizen of Switzerland, and a resident of Vienna, Austria-Hungary, have invented 5 new and useful Improvements in Electric Induction Heaters or Furnaces, of which the following is a specification.

In the case of induction heaters, in which the transforming of the current is effected 10 substantially outside the heater and the metal bath forms the short circuit connection of the secondary circuit, it is found to be of very particular advantage to utilize the metal heater or furnace casing as the 15 conductor of the secondary current to the metal bath. The self induction of the extended metal bath that is to be heated is thereby substantially lessened, as the introduction and return of the current can be 20 effected as near as possible to the bath and along the same. The metal conductive furnace-casing surrounds the metal bath that is to be heated almost concentrically and acts on all sides so as to reduce the self induction. 25 Moreover, the large surface of the conductive furnace-casing effects a good natural cooling of this fixed length of secondary current conductor. Further the causing of the furnace casing to take part in the conduct- 30 ing of the current renders the construction of the furnace cheaper and simpler. The furnace casing may be so constructed that it can carry the whole secondary current, or in addition to the furnace-casing further 35 special current conductors for instance as shown in Fig. 4 surrounding the sides thereof may be arranged for supporting it. Finally it is not necessary that the whole furnace-casing should be employed in conduct- 40 ing the current, but the casing may consist of elements which conduct the secondary current and of elements which are not caused to take part in the conducting.

An example of such a furnace or heater is 45 illustrated in the drawing, Figure 1 being

a longitudinal vertical section, Fig. 2 a plan, and Fig. 3 a transverse section, and Fig. 4 a transverse section of a form of the furnace in which only a portion of the casing is employed as secondary current conductor. 50

1 indicates an extended furnace tube in which the metal 2 to be heated by the current is contained. At the ends of the tube water cooled poles 3 are arranged, which transmit the induced secondary current on the one 55 hand from the secondary winding 6 and on the other hand through the furnace-casing 4 to the metal bath 2.

5 is the primary winding of the transformer. 60

As shown in Fig. 4 only a part of the furnace casing needs to be caused to act as a conducting length for the secondary current circuit.

The furnace may of course be constructed 65 so that it will turn or tilt, for instance by suspending it between the forks 7 of a revolving member 8 rotating in the socket 9, Fig. 4, and the bath be moved during the heating. Moreover, the furnace chamber 70 above the bath may be enlarged for the employment of fuel.

Having now particularly described and ascertained the nature of my said invention and in what manner the same is to be performed, I declare that what I claim is: 75

An electric induction furnace comprising an elongated furnace casing surrounding the metal bath, concentrically for reducing the self-induction, a transformer, water cooled poles at the ends of said casing for transmitting the induced secondary current through the furnace casing to the bath to be heated, substantially as described. 80

In testimony whereof I affix my signature in presence of two witnesses.

ALOIS HELFENSTEIN.
